UNITED STATES PATENT OFFICE.

WILLIAM G. HOUSKEEPER, OF NEW YORK, N. Y., ASSIGNOR TO WESTERN ELECTRIC COMPANY, INCORPORATED, OF NEW YORK, N. Y., A CORPORATION OF NEW YORK.

ELECTRON-DISCHARGE DEVICE.

Application filed June 7, 1923. Serial No. 643,871.

This invention relates to electron discharge devices, pertaining more especially to devices of this character capable of handling large amounts of power and has for its object an improved grid electrode and electrode supporting structure.

This object is attained by providing a grid electrode sufficiently sturdy that it may be supported from one end only and providing a cathode supporting structure within the grid supported independently thereof. A sufficiently sturdy grid electrode for this purpose consists of a cylindrical network comprising a plurality of overlying wire helices having parallel turns and having intersecting turns and a plurality of frame wires to which intersecting turns are attached. The frame wires are supported from an insulating member from which is also supported a cathode supporting structure arranged within the grid electrode. Because of the rigidity of the grid electrode, no connection is required between the unsupported ends of the grid and the cathode structure, thereby increasing materially the insulation between these two elements.

Referring now to the drawings, Fig. 1 is a sectional view, partially broken off, of an electron discharge device embodying the invention; Fig. 2 is an enlarged detail of a section of the grid electrode in the process of manufacture; Fig. 3 is a section on the line 3, 3 of Fig. 2, and Fig. 4 is an enlarged perspective disclosing the manner of attachment of the grid turns to the frame wires.

The enclosing vessel of the device comprises a substantially cylindrical glass portion 10, and a substantially cup-shaped metallic member 11 sealed thereto at 12, the member 11 serving as the anode of the device. A reentrant stem 13 projects into the glass portion 10 and is surrounded by a metallic collar 14 which is frictionally held in position on the stem. A plurality of rods 15 are supported from the collar 14 and in turn support a disc 16 of insulating material. A plurality of rods 17 project from the disc 16 a short distance into the metallic member 11. Welded to the ends of the rods 17 are the frame wires 18 of a grid electrode 19, the structure of which will be later set forth in detail. A pair of wires 20 are carried by the disc 16 and extend substantially the full length of the anode 11 and support a second disc 21 of insulating material adjacent the

closed end of the anode. A plurality of rods 22 symmetrically arranged with respect to the wires 20 project from the disc 16 to a point near the adjacent end of the grid 19. The disc 21 carries a pair of hooks 23 and a cathode 24 is strung back and forth between the rods 22, hooks 23 and a hook 25 carried by one of the rods 22.

The grid electrode 19 comprises a wire mesh cylinder made up of a plurality of 65 overlying helices having parallel turns and having intersecting turns. Preferably, this electrode is formed from a single length of wire 26 wound into a succession of helices, the turns of the alternate helices being 70 oppositely directed and the turns of each helix being offset from the turns of the preceding similar helix. In manufacturing this grid, one end of the grid wire is fastened to a mandrel which is rotated while the grid wire is 75 fed back and forth throughout its length to form the overlying helices. The portions of the wire comprising the ends of the helices are fastened together by a tie wire while the grid is still on the mandrel. Also before removing the cylindrical network from the mandrel the frame wires 18 are attached thereto by means of a tie member. This tie member comprises a pair of sinusoidally shaped 80 lengths of wire 27 which alternately pass 85 over and under each other, said wires being moved apart laterally until oppositely facing bends thereof engage each other to form interlinkings at each completed cycle, the remaining bends of one wire being opposite 90 the remaining bends of the other. This tie member as shown in Fig. 2 is laid on the cylinder 19 along a line of intersection of the turns of the component helices with each set of opposed bends resting on the turns of wire at 95 either side of their intersection. The interlinkings lie within the periphery of the cylinder in a groove provided in the mandrel. A supporting wire 18, the end of which has been pointed, is threaded between the intersecting turns of wire and the interlinking turns of the tie member. The introduction of the frame wire causes the tie member to assume the position shown in Fig. 3, and binds the turns of the helices against the frame 100 wire 18. The final relationship of the tie wires, frame member and lateral wires is shown in detail in Fig. 4. This completes the manufacture of the grid electrode and after its removal from the mandrel the frame 105

110

wires 18 are welded to the supporting wires 17 to complete the electrode assembly.

A grid electrode constructed in accordance with the above disclosure is sufficiently rigid that it need be supported from one end only and it is therefore possible to dispense with any connection between the remaining end and a supporting structure. One of the main reasons for the sturdiness of this grid lies in the fact that each portion of wire between points of attachment to the frame members forms with a similar portion of wire and a frame member a substantially triangular figure which is of greater mechanical strength than any of the other geometrical figures. These triangles overlap each other so that a plurality of parallelogrammatic figures are formed by the intersecting portions of wire. This overlapping feature of the wires also contributes materially to the production of a rigid network.

The invention claimed is:

1. A grid electrode comprising a plurality of overlying helices having parallel turns

and having intersecting turns, a frame member and a pair of wires alternately passing over intersecting turns of said helices and being fastened to each other behind said frame member.

2. A grid electrode comprising a cylindrical network composed of a single wire wound back and forth to provide a plurality of overlying helices having parallel turns and having intersecting turns, a frame member and a tie member passing alternately over intersecting turns and behind said frame member.

3. In an electron discharge device, an insulating disc, a pair of rods attached to said disc adjacent the center thereof, a second insulating disc carried by said rods, a grid electrode supported by said first insulating disc and surrounding said second disc but out of contact therewith, and a cathode supported by said insulating discs.

In witness whereof, I hereunto subscribe my name this 29th day of May, A. D., 1923.

WILLIAM G. HOUSKEEPER.
